(57) **CLAIM**

The ornamental design for a memory storage assembly panel, as shown and described.

DESCRIPTION

FIG. 1 is a perspective view of a memory storage assembly panel showing our new design;

FIG. 2 is a right side view thereof;

FIG. 3 is a left side view thereof;

FIG. 4 is the top view thereof;

FIG. 5 is front view thereof; and,

FIG. 6. is a bottom view thereof.

The broken lines shown in the figures are for illustrational purposes only and forms no part of the claimed invention.
